TENDER

Elmer E. Hicken, Collingswood, N. J.

Original application February 27, 1936, Serial No. 65,992, now Patent No. 2,159,738, dated May 23, 1939. Divided and this application June 3, 1938, Serial No. 211,687

2 Claims. (Cl. 105—237)

This invention relates generally to locomotive tenders equipped with stoker troughs and more particularly to a coal slide construction therefore, and it is an object of my invention to provide an improved combination of structural shapes and plates so formed, arranged and interrelated that the same may be effectively assembled and secured together to form an efficient and rugged construction that is functionally adapted to reduce the vibration and stresses imposed upon the usual narrow side floor strips adjacent the coal opening leading to the stoker trough, thereby avoiding leaks at the juncture between the floor sheet and the walls forming water containing portions of the tender tank. This application is a division of my application Serial No. 65,992, filed February 27, 1936, which has matured into U. S. Patent No. 2,159,738, granted May 23, 1939.

Other objects and advantages will be more apparent to those skilled in the art from the following description of the accompanying drawings in which:

Fig. 1 is a longitudinal vertical section of a tender embodying my improved construction and arrangement, taken substantially on the line 1—1 of Fig. 2;

Fig. 2 is a horizontal section taken substantially on the line 2—2 of Fig. 1;

Fig. 3 is an end elevation of the front end of the tender and underframe, the front of the tender being at the right end of Figs. 1 and 2 and parts of the coal space floor and slides being shown in section;

Fig. 4 is a longitudinal vertical section of my improved coal slide guide stiffener taken on lines 4—4 of Figs. 2 and 3;

Fig. 5 is a perspective looking down on the stiffener of Fig. 4.

In the particular embodiment of the invention, such as is disclosed herein merely for the purpose of illustrating one specific form among possible others that the invention might take in practice, I have shown in Fig. 1 a tender (without its trucks) having an underframe generally indicated at 1 carrying a tank generally indicated at 2. The details of construction of the underframe and tank do not specifically enter into the invention of this application, and hence it will suffice to briefly point out that as shown in said parent application the tank extends along each side of the center sill 3 and forwardly as at 4 beneath a stoker trough 5 and along each side thereof as shown in Fig. 2 at 6. The coal space 7 has a usual inclined rear wall 8 and usual narrow side coal floor strips 9 which form the upper

wall of the stoker trough 5 and join the walls of the water spaces 6, 6.

Instead of providing a single continuous coal opening as in the prior art, I provide a series of coal openings 10, Figs. 2 and 3, formed in the coal space floor 9 and separated by narrow transverse plate strips 11, Fig. 4. Coal is fed by gravity successively through said openings which are opened one at a time by means of usual movable sectional slides 12 supported by and between guides 13 and retaining plates 14, Fig. 3. For many years the prior art single opening has had the serious objection of causing the juncture of the floor plate and tank walls to be inherently weak, but no suitable arrangement has been heretofore suggested to reinforce the same because of obstructing or of retarding flow of coal to the openings or of making it difficult to shovel coal from the coal space floor 9 in case the fireman is required to supplement the action of the stoker by touching up the fire. To overcome the above objections I propose to use transverse plate strips 11 connected to floor plates 9, preferably as an integral part thereof cut in the same plane, thereby providing the several openings 10. These transverse strips carry direct tension forces to avoid spreading of the side walls and then in order to vertically protect these strips as well as to permit a hand shovel to pass thereover, I propose braces 15 having any suitable curved or angular upper surface herein broadly referred to as inverted V-shaped members, specifically angle irons disposed over each strip of floor plate left between the openings 10. The form of these members may, of course, vary, but the principal feature thereof is to vertically protect the strips 11 and to have a shape that allows a hand shovel to readily pass over the openings. The ends of the inverted angle irons are flattened as at 16 and preferably welded to the floor plate 10 so as to overlie the strips between the openings.

The foregoing arrangement has the advantage that the strips 11 minimize spreading and resist vibrations and abnormal stresses which create serious leakage problems while the inverted V-shaped upper surfaces of the members 15 give maximum and complete protection to the strips 11 and insure minimum obstruction to the flow of coal through the openings 10 as well as to permit the edge of a shovel to pass readily thereover. It has been found in actual practice that these functions and results are effectively obtained with minimum cost and complications together with maximum compactness, all of which has eliminated leaks at the juncture between the

floor sheet and the walls forming the water containing portions of the tank. To repair such leaks in the past has increased maintenance costs as well as requiring the tender to be withdrawn from service.

From the foregoing disclosure, it is seen that I have provided a combination whose component elements are so formed and structurally and functionally interrelated that their cooperative 10 action effects a compact and sturdy structure.

It will of course be understood that various changes in details of construction and arrangement of parts may be made by those skilled in the art without departing from the spirit of the 15 invention as set forth in the appended claims.

I claim:

1. A tender comprising, in combination, means forming a longitudinal coal space provided with a coal floor with openings therein, means forming 20 a conveyor chamber bounded on the top by said coal floor, flat floor strips extending transversely of said openings, sectional slides for said openings, means disposed adjacent to the edges

of said openings beneath said strips to provide guideways for said sectional slides which slidably extend beneath and in substantially close proximity to said strips, and transversely disposed inverted members of substantially V-shape in cross-section secured to the top of said floor and overlying said strips whereby coal may be substantially vertically guided by said inverted transverse members from said coal space through said openings and into said conveyor chamber 10 or coal may be removed manually from said coal space by a shovel moved longitudinally of said coal space and guided over the inclined surfaces of said inverted transverse members upon engagement therewith. 15

2. The combination set forth in claim 1 further characterized in that the ends of said inverted V-shaped members are flattened to provide a contact surface with said coal floor, and means for securing the flattened ends and floor 20 plate together.

ELMER E. HICKEN.
